UNITED STATES PATENT OFFICE.

CARL O. LINDSTROM, OF CHICAGO, ILLINOIS.

DISINFECTING OR PERFUMING APPARATUS.

1,100,751.

Specification of Letters Patent. Patented June 23, 1914.

Application filed November 29, 1912. Serial No. 734,012.

To all whom it may concern:

Be it known that I, CARL O. LINDSTROM, a citizen of the United States, and a resident of the city of Chicago, in the county of

5 Cook and State of Illinois, have invented certain new and useful Improvements in Disinfecting or Perfuming Apparatus; and I do hereby declare that the following is a full, clear, and exact description of the 10 same, reference being had to the accompanying drawings, and to the numbers of reference marked thereon, which form a part of this specification.

Disinfection of rooms has been accomplished by placing cloths saturated with the disinfectant in the room and sometimes suspending the same. Where disinfection is accomplished in this manner, the atmosphere surrounding the impregnated or saturated cloth or sponge becomes more or less charged with the disinfectant; if the disinfectant be volatile, while where the atmosphere in parts of the room more distant may contain a much smaller percentage of 25 the disinfecting material. Particularly is this true when rooms are sealed for disinfecting, inasmuch as the movement of the air within the room becomes very slight or ceases altogether. In consequence, adequate 30 disinfection may take place in one part of the room, for example, in the immediate environment of the disinfecting material, while other parts of the room may be insufficiently treated.

35 The object of this invention is to afford a disinfecting apparatus whereby a definite charge of the disinfecting material may be delivered to the atmosphere and intimately mixed and distributed through the atmosphere so that all parts of the room receive equal treatment.

It is an object of the invention to afford a device whereby the circulation is maintained in the room after the sealing of the 45 same for disinfection and whereby the charge of disinfecting material is delivered to the air at the point of greatest circulation to permit distribution throughout the entire room or space to be treated.

50 It is also an object of the invention to afford mechanism whereby a predetermined

amount of the disinfecting fluid may be delivered, the amount, of course, depending upon the size of the room or space to be treated.

55 The invention also has for its object a mechanism whereby a constant treatment of the air may be afforded for remedial or curative effect or to perfume the air, as preferred.

60 The invention (in a preferred form) is illustrated in the drawings, and hereinafter more fully pointed out and defined in the appended claim.

65 In the drawings: Figure 1 is a side elevation of a device embodying my invention. Fig. 2 is a front elevation thereof. Fig. 3 is an enlarged vertical section illustrating the controlling and regulating means for delivery of the fluid from its container. Fig. 70 4 is a section on line 4-4 of Fig. 3. Fig. 5 is an enlarged, vertical section taken through the wick holder and supporting clamp. Fig. 6 is a fragmentary view in side elevation of the wickholder illustrated in Figs. 2, 3, and 75 4, and illustrating a slightly modified clamp.

75 As shown in the drawings: 1, indicates an ordinary electric or other power driven fan, provided as usual, with any suitable guard, which may be constructed of wire, 80 indicated by 2, in Fig. 1, in which a vertical wire is shown connected to the frame of the fan and extending down over the front thereof.

85 The guard illustrated in Fig. 2, comprises, as shown, a wire frame consisting of a ring 3, of wire supported outwardly in front of the fan and extending around the same, and connected transversely or diametrically across the front of the fan by radial wires 90 4. The container for the disinfectant or other liquid, is supported on the fan guard as hereinafter described, and comprises a cup 5, to contain the liquid, having a base 6, provided with a small central passage 95 opening therethrough, in which extends a hollow member 6^a having its lower end tapered at 6^b, said member and the surrounding collar 6^c of base 6 having registering apertures 6^d to permit the passage there- 100 through of the liquid. Said tapered lower end 6^b affords a seat, comprising what may

be termed essentially a needle valve. The stem 7 of said valve extends through the cap 8, of the container and through an adjusting nut 9, in a familiar manner, and is 5 provided at its upper end with a lever 10, whereby said stem 7, of the needle valve may be raised to permit the slow discharge of the contents of the container drop by drop, and for this purpose a sight feed 10 chamber 11, is provided below the needle valve, in which the drops of liquid can be seen to fall from the valve.

Threaded into the lower end of the sight feed chamber is a wick tube 12, and also 15 disposed on said tube below the collar 19 afforded by the sight feed chamber, is a washer 13, between which and the bottom collar on the sight feed chamber the guard wire 3, of the fan may be engaged, as shown 20 in Figs. 1, 3, and 5, to rigidly support the device in operative position in front of the fan. Loosely secured within the wick tube 12, is a wick 14, adapted to become saturated by the liquid discharged through the 25 needle valve from the container.

Should it be desired to support the device upon a vertical member of the fan guard, obliquely directed apertures are provided in the bottom flange or collar 19, of the sight 30 feed chamber 11, as shown in Fig. 6, and an oppositely inclined aperture in the washer 15, which is mounted on said wick tube. A nut 16, is provided on said tube, as shown in Fig. 6, so that the wire having been extended through said apertures, as indicated 35 in Fig. 6, the washer tilting upwardly at one edge to permit the same being passed therethrough, the nut may be set up, thus jamming the washer upwardly against the base 40 flange or collar 11, on the sight feed chamber and cramping said wire between the same, because of the obliquity of said respective apertures.

The operation is as follows: When used 45 for disinfecting purposes, for example, when it is desired to completely and thoroughly disinfect a room, the device is secured on the fan guard, as before described, and is filled with the required disinfecting liquid, usually 50 of a more or less volatile nature, and should the charge required for complete disinfection be more than the capacity of the container 5, a larger container 17, or in fact a tank, can or receptacle of any kind containing 55 the required amount of the liquid for the complete disinfection may be supported in any convenient way above the container 5, and connected to communicate with said container 5, through a tube 18, which, communicating 60 in said tank 17, discharges into the container through the filling aperture, the plug 20, for the filling aperture having been removed, of course, and the end of the

pipe 18, being threaded thereinto. The fan is now started in motion, and if desired, the 65 room may be sealed in the usual manner. The draft of air occasioned by the fan is directed in part upon the wick tube, and is driven through the wick carrying outwardly the vapor of the disinfectant contained in 70 the wick, and the rapid flow of air occasioned by the fan greatly facilitates the vaporization of such disinfectant. The needle valve, of course, is adjusted to deliver the liquid to the wick as fast as the same 75 may be taken therefrom into the atmosphere and the action is very rapid owing to the complete circulation of the atmosphere of the room because of the action of said fan. The amount of the disinfectant required 80 for the room may be easily determined from the measurements of the room itself, and the required quantity, of course, is placed in the container 17, if the container 5, is not of sufficient size. When all the disinfectant 85 has been taken up by the air of the room, the desired point of saturation will be reached, and the operation therefore completed.

Of course, when used for remedial treatment, as for example, charging the atmosphere of a room with a remedial agent to be inhaled, the needle valve is adjusted to give the required rate of discharge from the container to maintain the required percentage of the remedial agent in the atmosphere. With such use, of course, the room is not sealed and a somewhat larger portion of the remedial agent or medicament is required for that purpose. When so used, if desired, the fan may be placed at a window 100 opening to draw fresh air into the room to medicate the same to the desired extent and to deliver the same into the apartment. In the same manner a perfume may be used.

Of course, the wick tube may assume any 105 desired form, for example, it may be a simple metallic tube perforated on opposite sides to permit the air from the fan to be driven therethrough, as shown in Figs. 2, 3, 4, and 6, or if preferred, the wick tube may be constructed wholly or in part of wire gauze to properly support the wick by permitting a free flow of air therethrough from all directions.

Of course, the wick tube may be of any desired form in cross section, and if preferred, may be of greater diameter or width in a plane parallel with the fan than in a plane at a right angle therewith.

Of course, numerous details of the construction may be varied. I have shown but a preferred form of my invention. I therefore do not purpose limiting myself otherwise than necessitated by the prior art.

I claim as my invention:

A disinfecting and vaporizing apparatus,

comprising a foraminated tube, absorbent material therein, means for delivering liquid to be disseminated to said absorbent material, and a collar and washer on said tube 5 adapted to clamp said tube directly to a fan guard.

In testimony whereof I have hereunto

subscribed my name in the presence of two subscribing witnesses.

CARL O. LINDSTROM.
